YARN WINDING MACHINE

Louis M. Cotchett, Hingham, and Lester Campbell and Ferdinand F. Stange, Westfield, Mass., assignors to Foster Machine Company, Westfield, Mass., a corporation of Massachusetts

Application January 19, 1943, Serial No. 472,862

22 Claims. (Cl. 242—35.6)

1

The present invention relates to new and useful improvements in winding machines and more particularly to a novel and improved semi-automatic yarn winder.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1—A is a plan view of a typical and illustrative embodiment of the present invention and shows the preferred form thereof;

Figure 1—B is an end elevation of the head end or driving end of the machine;

Figure 1—C is a side elevation of Figure 1—B;

Figure 2—A is a fragmentary side elevation of some of the winding units and the tender, the upper portion only being shown;

Figure 2—B is the lower portion of the side elevation;

Figure 3—A is a fragmentary vertical section showing the upper portion of one of the winding units and the travelling tender;

Figure 3—B shows the lower portion of the vertical section shown in Figure 3A;

Figure 4 is a fragmentary sectional view of the upper portion of the tender and winding unit showing certain of the parts in several positions, and with many parts omitted for clarity;

Figure 4—A is a fragmentary vertical view of the narrow slot running longitudinally the duct and two slots running transversely across the duct intersecting the long narrow slot.

Figure 5 is a fragmentary top plan view of a winding unit showing the position of the strand of yarn, and with the outline of certain of the tender parts being superimposed on the view;

Figure 5—A is a fragmentary top plan view of certain of the parts showing the assembled yarn ends;

Figure 6 is a view similar to Figure 5—A showing the tender moved to a further position, the running thread or yarn having been joined and

2

knotted and with the running thread or yarn entering a tension and slubbing mechanism;

Figure 7 is a vertical sectional view through a winding unit and showing the yarn supply mass supporting means and tension device in side elevation;

Figure 8 is a fragmentary front elevation of the parts shown in Figure 7;

Figure 9 is a fragmentary vertical section showing a bobbin being doffed from the yarn supply mass supporting means;

Figures 10 to 20 are fragmentary views showing various positions of the cam means in different phases of their operation. Figures 10, 12, 14 and 16 are front elevations of the cams shown in side elevation in Figures 11, 13, 15 and 17, respectively, the stages of operation shown in the pairs of views being the same. Figure 19 is a fragmentary top plan view of the cam means and Figure 20 is a top plan view of the rack and pinion means shown in Figure 18;

Figure 21 is a top plan view of the yarn supply mass holding and replenishing means;

Figures 22 to 27 are elevations, with certain parts omitted, of the means shown in Figure 21, the successive views being taken from circumferentially spaced points corresponding to the position of the respective views. Figure 22 thus being taken along a line extending from the central shaft in Figure 21 to the same central shaft as shown in Figure 22;

Figure 28 is a fragmentary vertical section showing a winding unit in starting position;

Figure 29 is a similar view showing the winding unit in knocked-off position such as might be caused by exhaustion of the yarn supply;

Figure 30 is a side elevation of an assembly of parts showing the suction duct rocked ahead and down which movement brings the knotter into position for tying two strands of yarn.

Figure 31 is a front elevation, with parts removed, to show the knotter lowered to a position just prior to engaging the two strands of yarn before tying same together.

Figure 32 is a front elevation, similar to Figure 31, but with the knotter advanced, by the travel of the tender, to the position for engaging the two strands of yarn at the beginning of the knot tying operation.

Figure 33 is a front elevation, similar to Figures 31 and 32 but with knotter still further advanced, by the travel of the tender, to the position reached at the completion of the knot tying operation.

Figure 34 is a front elevation, similar to Figures 31, 32 and 33 but with the knotter in its normal

idle position up and away from its knot tying position.

Figure 35 is a timing diagram showing the time relation of the various operations of the tender and of the winding unit.

The present invention has for its object the provision of a novel and improved substantially automatic winding machine for winding yarn or other strand material into packages. A further object is the provision of a winding machine requiring a minimum of attention on the part of the operative, and which requires only the manual replacement of the fully wound packages with new cores on which the yarn is to be wound and the manual loading into the machine of new supply masses of yarn. The invention further provides a winding machine in which the free end of the yarn on a package may be easily found and picked up and the end of the yarn may be drawn off more readily than heretofore. Still another object is the provision of improved winding machine in which the replenishment, assembling and knotting operations are performed only on those units where the yarn has been exhausted from a supply mass or winding has stopped for other reasons.

Further objects of the invention are to provide selectively operable bobbin doffing means so that only those bobbins from which yarn is not being drawn are doffed; to provide an improved yarn end finding and drawing off means; to provide improved means for reversing the yarn package being wound during the yarn end assembling operation; and, among other objects, to provide for an improved, simplified winding machine which will wind at high speeds and produce a large number of wound packages economically.

In the preferred embodiment of the invention, here disclosed, the invention is illustratively applied to a multi-unit winding machine having a plurality of surface driven winding units arranged in a continuous series, each winding unit comprising a constantly rotating driving roll, a pivoted arm carrying a package core receiving spindle or shaft which can be lowered to bring the core into driving relation to the roll so that yarn or other filamentous material is wound on the package by the rotation of the roll and core. Usual yarn guide means are traversed back and forth across the surface of the package to wind the yarn properly on the core.

The winding package normally rests upon and is driven by the roll and is lifted and held away therefrom by a cam and latch mechanism to an idle or non-driving position upon any discontinuance of the flow of the yarn being wound as indicated and controlled by a yarn detector or drop-wire normally held in operative position by the running strand being wound.

The winding units are preferably identical and may be divided into two groups of about fifty each, the two groups facing in opposite directions, while the driving rolls for each group are aligned, mounted on and driven by a common shaft, each of the two group shafts being driven by a separate motor at the desired winding speed.

Adjacent each of the winding units is provided a support for a plurality of the yarn supply mass such as bobbins from which, in succession, yarn is supplied through suitable tension mechanism to the package being wound, passing over the yarn detector so as to prevent its moving into contact with a cam which actuates the latch lifting mechanism until the yarn has been exhausted or broken.

The yarn supply masses normally comprise spinning bobbins and the holder for them is formed as a rotatable member having, in a preferred arrangement, three parallel bobbin receiving pins, extending in a generally upward direction, each of the pins being adaptable to receive a bobbin. As one bobbin becomes exhausted, or the strand of yarn becomes broken, the holder may be rotated to bring the completely or an incompletely exhausted bobbin to an intermediate position and the same movement brings a reserve bobbin into winding-off position, the same movement also moving the exhausted bobbin through a doffing operation in which the bobbin is removed from the pin, said pin being rotated around to a loading position for a fresh supply bobbin.

When the bobbin is rotated into the intermediate position, it may be observed by the operative as to whether there is any yarn remaining thereon, so that option may be had for its proper disposition by hand. If sufficient yarn appears upon the bobbin to justify, the operative may place the bobbin in the reserve position so that it will be subsequently moved into running-off position and the drawing off of the yarn resumed.

If, however, there is no yarn on the bobbin the operative ignores it and it is doffed from its supporting pin in the same movement which brings the supply bobbin into the running-off position and the exhausted bobbin into the intermediate or observation position. The pins are preferably pivotally mounted on their holder, with the axis of the holder such that the pins are slightly inclined and means are provided for swinging the exhausted bobbin and pin downward and outwardly as it moves through the doffing operation to the loading position, thereby providing for the exhausted bobbin to be thrown downwardly and to drop by gravity from the pin.

Adjacent the holder is provided a slide directed toward the reserve bobbin pin so that the operative need only drop the bobbin on the slide and it will be automatically guided onto the reserve bobbin pin thereby expediting the operative's work in replenishing the bobbins.

Cooperating with the several winding units in succession, and moving relatively to them is a tender, and means are preferably provided for moving the tender past the several winding units which are preferably fixed with reference to the machine frame. The tender is supported by and moves on a trackway, which trackway preferably extends along the multi-unit winding machine near its base and forms an endless track having two straight portions parallel to each other, one at either side of the machine, these straight portions being connected at the ends by curved track portions which provide an endless path, of generally oblong shape.

On the tender and near its lower portions is provided a motor which is drivingly connected with traction devices carried by the tender and engaging the trackway. Conventionally, the traction devices may be a belt supported by pulleys, the belt resting on one member of the trackway, and connected through variable ratio gearing to the motor so that the speed of travel of the tender past the winding units may be varied at will and adjusted to size of the supply package and speed of winding of the yarn or other filamentous material being wound (which is the duration of exhaustion), or the speed of the operative in handling the bobbin, or the most efficient combination of these factors.

The traction motor preferably receives its power

from a bus bar extending along and optionally forming part of the trackway, the return circuit being grounded, and power is preferably supplied at an inherently safe voltage so that no hazard is created in case the operative's body should short-circuit the power supply. Preferably the voltage is in the neighborhood of twenty-five volts, and this may be derived from a step-down transformer or otherwise.

The tender also includes a suction nozzle which is preferably relatively thin, of a width greater than the package being wound and is directed toward the package, so that after the yarn has been exhausted from a supply bobbin, the loose yarn end on the package may be automatically found and sucked into the nozzle by the current of air. While the suction nozzle may be of a width greater than the package being wound, it is accurately proportioned to directly control the length of the loose end of the yarn sucked and drawn from the wound package, so that the length may be sufficiently long to be tied up but is prevented from being unnecessarily long, thereby preventing waste of the yarn. To provide for the suction, the tender carries a blower which may be conveniently driven by the traction motor, or the blower may be electrically driven, independent of the traction motor, and the suction nozzle is connected to the intake side of the blower by an air duct extending for a considerable distance in a generally downward and outwardly direction away from the package.

Means are also provided for reversely rotating the package as the tender passes so that the entire periphery of the wound package may be explored for the loose end and, once the end is found, it will be unwound from the package through its reversed rotation. In the illustrative embodiment, an idle roll is mounted at the upper and forward portion of the tender-supported air duct, closely adjacent to the suction-nozzle, and means are provided for moving the roller between the package and its driving roll. With the package thus raised or in its non-winding position, these means also serve so to time the period of contact of the idle roller with the driving roll and package that only a predetermined length of yarn will be unwound from the package.

To expedite and insure the freeing of the yarn end from the surface of the package, a blowing nozzle is provided immediately next to the suction nozzle, the exhaust air from the blower is directed to flow along the top of the suction nozzle so that, when the suction nozzle is extended, an opening is formed by the mouth of the nozzle and its supporting casing so that the exhaust blast is caused to impinge tangentially across the periphery of the wound package before being drawn into the suction nozzle mouth, thereby considerably enhancing the sweeping action of the air current to blow free, lift and draw off the loose end from the wound package into the suction nozzle.

Means may also be provided for braking the package being wound during its reverse rotation so as to limit the amount of yarn drawn from the package immediately after the yarn end has been found and drawn off by suction. When the correct predetermined length of strand has been sucked and drawn from the unwinding package, cam means, carried in part by the tender and operated by the relative movement of the tender and winding unit, operate to apply a friction member against the package to stop its rotation, thereby preventing needless waste of yarn.

This arrangement of directing the exhaust blast is also advantageous as it promotes the removal of lint, dust and other foreign matter from the winding unit, since as the suction nozzle is retracted the blast may escape generally in the direction of winding units and the tension devices that respectively serve them, thus blowing off stray lint and cotton hairs before they may accumulate into "gouts" or "rat-tails" to be drawn into and interfere with the tensioning or stubbing means, or to be picked up by the flow of the yarn being wound and included in the wound package as a "slug" to give trouble in subsequent yarn processing operations.

In order to prevent recirculation of such foreign matter as may be drawn into the suction nozzle as well as yarns which are cut off in knotting the blower is preferably provided with a separator so that all such entrained material is removed from the air at the blower and is not blown cut to foul the winding mechanism from which it was removed.

Along the trailing edge and at the underside of the suction duct is provided a long narrow slot extending into the nozzle, and for a considerable distance toward the blower, and means are provided for engaging the yarn drawn into the suction duct and for removing it from the duct through this long narrow slot. For this purpose a second slot, parallel to the path of movement of the tender, intersects the long narrow slot, and a hook member is provided on each winding unit on the frame which hook may enter and pass through the second slot as the tender moves.

During this passage the hook engages the yarn lying in the duct so as to slide the yarn laterally of the duct and finally through the long narrow slot, the length of yarn having been determined by the period of contact of the idler roll with the driving roll and package, and being more than sufficient to extend past the second slot. Preferably this yarn engaging and removing hook also holds and carries the leading end of the yarn from the reserve supply bobbin so as to assemble the leading end of the reserve yarn supply with the exhausted end of the yarn wound on the package, thereby positioning the two yarn ends readily for tying, either manually or by a mechanical knotter.

The knotter may be of conventional design, and is preferably mounted on the tender so as to receive, engage, and tie the assembled yarn ends into a secure knot of the desired type, after which the surplus yarn beyond the knot is trimmed in the usual manner. Where a mechanical knotter is used and carried by the tender, it is preferably actuated in correct timed relation, by the travel of the knotter past the winding unit.

Thus each winding unit continues to wind yarn from a supply mass or bobbin onto a package by contact of the package with the driving roll, and when the yarn supply has been exhausted, the supply holder is rotated to move the reserve yarn supply into winding-off position, simultaneously moving the exhausted bobbin into an intermediate position for inspection as to its completion of exhaustion and the previous intermediate bobbin is doffed from its supporting pin by the tilting of the pin said pin is then restored to its upright position by the same movement, ready to receive a new supply mass dropped onto it through the slide by the operative. As the operative drops the new bobbin into place, its leading yarn end is held and preferably placed in the

hook to ready it for the subsequent passage of the tender and knotter.

During the winding operation the tender moves continuously past the various winding units in succession, and if operated sufficiently slowly with reference to the speed of winding and the length of yarn on the supply mass, the supply mass will have been exhausted by the time the tender reaches each winding unit. As the tender comes to a winding unit, the idler roll is moved forward to reverse the then idle package, winding of which has been stopped by operation of the detector mechanism due to exhaustion of the yarn. As the idler is moved forward, the suction nozzle is moved close to the periphery of the package, thereby freeing the exhausted yarn end and sucking it into the suction nozzle, and the duration of contact between the idler roller, driving roll and package is regulated in conjunction with an unwinding package braking mechanism, to draw off the proper length of yarn. Continued movement of the tender causes the hook carrying the reserve yarn end to move through the suction duct and to engage and assemble the sucked off exhausted yarn end, properly spaced and parallel, with the reserve yarn end. Further movement of the tender brings the knotter into operative relation with the assembled yarn ends where they are tied and trimmed.

After the yarn ends have been securely tied, travel of the tender resets the winding mechanism so that winding of yarn on the package from the supply mass is resumed.

Because of the factor of end breakage it may be desirable to cause a tender to pass the winding units more frequently than is necessary to insure that all of the yarn supply masses will have been invariably exhausted in succession when the tender comes into operative relation with each winding unit. To provide for this more efficient operation selective means are provided for causing operation of the yarn assembling, supply mass renewing, package reversing, and knotting mechanisms only when the package is idle or the yarn detector indicates the absence of a running yarn.

For this purpose means are provided cooperating with the tender and controlled from the yarn detector, preferably through the starting lever by which the idle package is brought into driven position with respect to its driving roll. As embodied the starting lever has a running position and an off position, the cam means are provided on the tender to be engaged by the starting lever only in its off position, this engagement being necessary, in the illustrative embodiment, to cause actuation of the various tender-carried parts cooperating with the winding unit.

If the yarn has been exhausted, and the detector has caused movement of the package to be raised to its stopped or idle position, the tender carrying mechanisms are engaged by the starting lever in its consequent off position, and thereby causes actuation of the various tender-carried parts. A cam cooperating with the stop lever in its off position and carried by the tender rocks the air duct and nozzle, as well as the reversing idler into operative position, and also lowers the suction nozzle so that the yarn assembling hook passes through the second slot to remove the exhausted yarn end from the air duct, as well as to cause the yarn ends to be tied together by the knotter in case the knotter is carried by the tender.

Other means are provided for rotating the

reserve yarn supply or bobbin into winding-off position when the starting lever was in off position as the tender passed, but not otherwise. Also cam means are provided for resetting the starting lever as the final operation of the tender on the winding unit, these means operating, of course, only in case the starting lever is not already in running position.

An abutment is provided and carried on the tender to move the starting lever into its running position during a portion of the time the tender passes. With the starting lever in its running position, the tender passes idly by the winding unit, the suction and blowing nozzles, and the reversing idler being spaced from the package so as to cause no disturbance of the winding, and the yarn assembling hook being spaced from the intersecting slots.

It is generally desired to wind the yarn with some tension and to slub the yarn and a tension and slubbing device is provided between the yarn supply and winding package, and preferably between the knotter and winding package, and means are provided for insuring that the assembled and tied yarns are correctly threaded through the tension and slubbing means. These means also operate to pass the knot beyond the tension and slub catching device, thereby preventing snagging of the knot and consequent breakage of the yarn.

In the illustrative embodiment, means are also provided for receiving and collecting the doffed bobbins and for this purpose a bobbin box is articulately mounted trailing the tender and moved with the tender. This bobbin doffing box may be provided with a separate compartment to carry full bobbins to be placed on the reserve spindles or yarn supply pins. In this way, the operative follows the tender and manually removes a full bobbin from the supply box, places it in the slide and allows it to drop onto the reserve bobbin pin of the successive winding units after the tender has passed.

When a unit is winding yarn means may also be provided for preventing movement for rotation of the yarn supply holder so as to prevent the idle feeding of a reserve bobbin to running position which would result in breaking the winding strand and in the doffing of a partially filled bobbin on the next passage of the tender past the winding unit.

It will be understood that the foregoing general description and the following detailed description as well are exemplary and explanatory of the invention but are not restrictive thereof.

Referring now in detail to the accompanying drawings which show the present preferred embodiment of the invention there is provided a multi-unit winding machine having a plurality of winding units 50 arranged in two parallel aligned series facing in opposite directions with the back sides of the winding units of one series adjacent to the back sides of the winding units of the other series.

These winding units are of substantially conventional construction and each comprises a driving roll 32 carried and driven by shaft 33 which is rotatably journaled in bearings 34, all of the rolls 32 for a given series being mounted on a single shaft 33, each shaft 33 of each of the two series is preferably driven by a separate motor 36 through a belt 37. Bearings 34 are mounted on a unit frame 39, and these unit frames are securely fastened to the main frame 40 of the machine.

For rotatably supporting the core 44 on which the package 45 is to be wound, there is provided a wooden core 42 (or an iron cone shell not shown) which is freely rotatable on a spindle 43 pivotally supported in the end of an arm 46 which is rotatably mounted by means of collar 47 on a shaft 48, extending from one end of the machine to the other, the arms 46 being held against easy movement by a heavy spring 49 fast to the collar 47 and having a rolled end 50 which rides in the groove 51 of collar 52 fast to the shaft 48. The arms 46 for each series of winding units are mounted on the common shaft 48, but extend therefrom in opposite directions, and hold the cone spindle 43 at such an angle that substantially full contact may be established between the package core 44 and the driving roll 32, thereby rotating the package core by frictional contact with its surface to wind yarn on the package.

Means are provided for traversing the yarn 20 throughout the desired distance on the package core and for this purpose a cylindrical traverse cam is mounted adjacent to the driving roll 32 and in parallelism therewith, the traverse cams for all of the winding units of each series being 25 mounted on and driven by a common shaft 55 which is driven from a motor 36 by a V belt 37 provided with means to automatically recurrently vary the speed of cam shaft 55. The traverse cam and thread guide may be of conventional construction but in the illustrative embodiment comprise a thread guide 60 having a central thread guiding slot 61 and curved sides 62 supported at the end of a finger 64 which is reciprocated in a controlled varied timed relation to the rotation of shaft 33 by means of the usual cam groove in the cylindrical cam 56 on shaft 55. Thus as the package is rotated by the driving roll 32, yarn Y is traversed back and forth along the length of the package core by the 40 thread guide 60 to lay it on the package in uniform layers.

The yarn supplied for winding is illustratively carried on bobbins 70 which are tubular and have a mass of yarn 71 thereon, being shown as the 45 type of bobbin which would be produced by conventional spinning machines. Three of these bobbins may be supported on movable bobbin supports, which comprise a base 73 rotatably mounted on a shaft 74 which projects in a generally upwardly direction from a bracket 75 fixed to and supported by rod 76 extending along the lower part of the machine frame 40. Base 73 is provided with three equally spaced radially extending pins 77 on each of which is pivotally mounted a plate 78 from which extends upwardly a bobbin receiving pin 79 which loosely projects into the tubular portion of the bobbin.

From one side of each plate 78 projects a stop pin 80 engageable with a radially extending pin 60 carried by the base member 73, and all of the bobbin pins 79 and their bobbins are held in substantial parallelism by means of the pins 80 and 81 and by an interrupted cone 83 cooperating with a collar 84 between which the base rotates. Cone 83 and collar 84 are fixed to the lower end of the shaft 74 and also form the bearings for the base 73 as it rotates. Cone 83 fits closely against the bottoms of the plates 78 and prevents their turning on their pivot pins 77 so 70 long as the plates are in contact with the ring 83, but is cut away, as at 85 so as to permit the plates 78 to turn for doffing the bobbin. A spring pressed ball 87 mounted in a socket 88 in the lower portion of the cone 83, cooperates with 75

shallow depressions 89 in the base 73 to insure correct indexing and accurately hold the bobbin pins 79 in proper position against accidental displacement.

5 On the lower portion of the machine frame 40, and preferably on the outermost uprights 150, is mounted a lower rail 151 supported by brackets 152 and an upper rail or channel 154 supported by brackets 155, the rails 151 and 154 being substantially parallel to each other and spaced a considerable vertical distance apart. The rails 151 and 154 extend along one side of the winding machine, and curve gradually to meet another straight section of each rail extending along the other side of the winding machine, and a second curved section of both rails is provided at the other end to form a closed double trackway. Both the rails 151 and 154 are preferably horizontal, and the curved end portions 156 are preferably semi-circular and spaced sufficiently from the ends of the winding machine to provide ample room for turning of the travelling tender.

10 The lower rail 151 is preferably relatively narrow on its upper face while the upper rail 154 is a bent section having its channel opening downwardly and provided on its inner surface with insulating material 158 extending along the inner side surfaces of the rail 154, the outer insulation 158 supporting a conductor 159 or bus bar through which it and the rail 151 current is supplied to power the tender.

15 The tender 160 comprises a support member 161 from which downwardly extend two caster stud yokes 163 in each of which is rotatably journaled on a horizontal axis a pulley 164, these pulleys being aligned to ride on the rail 151. Above the support member 161 is a plate 166 from which upwardly extend two spaced apart follower arms 168, at the inner and upper ends of each of which is rotatably mounted roller 169, both rollers 169 being received within the channel of rail 154, and bearing against the bus bar 159.

20 Power is supplied to the motor from the rail 151 through the pulleys 164 which are grounded with respect to the tender frame, and the circuit is completed through the rollers 169 which are connected to the motor by conductor 170, the follower arms 168 being insulated from the tender frame.

25 In order to permit the rails 151 and 159 to be relatively exposed, and at the same time provide safety for the operative and equipment, the current supplied to the motor through these rails is preferably at a relatively low and inherently safe voltage, such as twenty-four volts and the current is supplied from the mains to these conductors through a suitable step-down transformer 171.

30 Supported on a bed plate 175, forming the lower part of the tender, is the traction motor 177 which drives the traction pulleys 164 through variable speed reduction gearing 178 and belts 179, 180. Belt 180 runs under both pulleys 164, and over the driving pulley 181, and its lower horizontal reach is in contact with the upper surface of rail 151 so as to assist in the movement of the tender along the rails.

35 Each of the caster stud yokes 163 is preferably adjustably mounted in a bracket block 162 on the support member 161, so that their relative vertical position may be varied to accurately adjust and level the tender on the rail.

40 As power is supplied to the motor, the tender

is moved continuously around the two series of winding machines, and its speed is such that it preferably completes each trip around the machine in approximately the same time as is required for the normal wind of one of the supply bobbins. While these times are preferably substantially equal, some advantage, in many cases is realized through having the tender make its complete trip in a slightly longer time than is required for the winding off of the average bobbin, thereby assuring when the tender approaches a particular winding unit, the respective active bobbin has been completely exhausted.

New bobbins may be brought into a yarn supply position, and the exhausted bobbins from which the yarn has been wound may be doffed by rotation of the base member 73 carrying with it the three bobbin pins 79. The cone member 83 on its underside is provided with a cutaway portion 85, this cutaway portion being sufficiently large to allow the bobbin pin supporting plate 78 to turn from the position shown in Figure 7 to the position shown in Figure 9.

For effecting this movement, each of the plates 78 is formed on its underside with a tripper lug 90 which engages with a tripper 91 mounted on an arm 92 and the plate swings out of the cutaway portion 85 which extends from collar 84, and is adapted to engage and tilt the pin support block 78 as it rotates from one winding position to another. With the pin 79 in lowered position (Figure 9), the empty bobbin is doffed therefrom, and as the bobbin support continues to rotate, an upper edge of the tilted plate 78 engages with the lower edge 86 and cut-away portion 85 so as to restore the pin 79 to its generally vertical position before the support has moved to its next yarn feeding position.

The successive positions of the bobbin holder and its principal parts are shown in Figures 21 to 27. In these figures, Figure 21 is a view looking from above axially of the shaft 74. Figures 22 to 27 are different side elevations and are arranged radially of the circumferential position from which they were taken.

Figure 22 shows the bobbin support pin 79 in its normal position, and in normal operation it would be supporting an exhausted bobbin, where it can be inspected by the operative, who removes it in case there remains on it a considerable quantity of yarn.

Figure 23 shows the same bobbin pin 79 after it has moved slightly from its normal position, and in the position shown the tripper lug 90 is ready to engage the tripper 91, while the plate 78 is so related to the cutaway portion 85 that the plate 78 and its bobbin supporting pin 79 are free for pivotal movement.

In Figure 24 the tripper lug 90 engaging with the tripper 91 has caused the bobbin pin 79 to be moved to bobbin doffing position, and the empty bobbin is thrown off and falls by gravity.

Figure 25 shows the forward edge 86 of the cutaway portion 85 engaging with the upper face of block 78 so as to restore the block to its normal position with the bobbin pin 79 in substantially vertical position.

Figure 26 shows the plate 78 and the bobbin pin 79 restored to normal position with the bobbin pin parallel to the supporting shaft 74, and in this position the bobbin pin 79 is ready to receive a new supply bobbin or other package.

Figure 27 shows the position of the parts with the bobbin in normal supply position, and it is

from this position that the yarn is wound onto the package.

During the movement of each bobbin pin from the position shown in Figure 26 to the position shown in Figure 27, the bobbin pin 79 remains parallel to the shaft 74, and similarly the bobbin supporting pin 79 remains parallel to the shaft 74 as the pin is moved from the position of Figure 27 to its inspection position in Figure 22.

While the movements of the bobbin pin and associated parts have been described only with reference to one pin 79, the movements of the other pins and their associated parts are exactly similar as they pass through the positions shown in Figures 23, 24 and 25. During the major portion of the winding operation the three bobbin supporting pins 79 are at rest in the positions corresponding to those shown in Figures 22, 26 and 27.

As the yarn is drawn from the active bobbin it passes upwardly, over a guide bar 342, between the tension washer 351 and the bottom washer 349, over the thread bar 103 and is guided onto the package by the traversing guide 60.

The traverse mechanism is shown more in detail in the prior patent to McKean 1,992,757, the structure of which is substantially duplicated here. The prior patent to McKean shows a typical form of drive for the driving roll 32 and the cylindrical cam 56.

Likewise, the stop motion, for moving the package being wound out of contact with its driving roll 32 when the yarn breaks or the supply has been exhausted may be a substantial duplicate of that shown in the prior patent to McKean 1,992,757, and except for the starting handle 110 and rack 104 is as there shown. In the present embodiment, however, the rack 104 is positioned rearwardly relative to the position of package 45 to provide greater clearance of the bobbins, the rack lifter 105 is correspondingly moved and an additional rack finger 106 is pivoted on the frame 39 and is connected by link 107 to the lower end of arm 108 depending from the starting lever 110 so that rack 104 is lifted and moved forwardly as the starting handle is raised on exhaustion of the yarn, or other occurrence which allows raising of the detector finger on dropwire 112.

Means are also provided for automatically rethreading the yarn guide 60 as the winding is restarted, and such means may be constructed in accordance with the patent to McKean 1,992,757 and are so shown. Thus each of the winding units has friction means for driving the package by its surface, and for winding on the package a yarn which is traversed by a reciprocating thread guide, while the yarn is drawn through the tensioning mechanism from the active one of a plurality of yarn supply masses or bobbins.

Each unit is also provided with means for automatically raising the package out of contact with its driving roll to stop its winding when the yarn breaks or is exhausted from the active supply bobbin, and other means are provided acting on the yarn, and operated by the stop motion for positioning the yarn so that it will be automatically introduced into the reciprocating thread guide 60 as the winding is restarted.

The several positions of the parts in relation to the stop motion and thread bar are shown in Figures 3-A, 28 and 29.

In Figure 28 the starting handle 110 has been fully depressed so that the rack lifter 105 has disengaged the teeth of rack 104 from the rack

finger 106 thereby permitting the package to drop onto the driving roll 32, and at the same time the latch mechanism has been moved into a position so that upon the release of the starting handle the latch mechanism will be set to hold the starting lever in running position under control of the dropwire 112.

Figure 3—A shows the position of the same parts after the starting handle has been released, and while the machine is in operation. As will be noted the thread bar 103 has been lowered so that the thread now runs in the slot 61 of guide 60; also shows the parts in running position, with the dropwire 112 held in lowered position by the tension of the thread.

Figure 29 shows the parts in stopped position with the package raised out of contact with the driving roll 32, drop wire 112 having raised to its upper position as soon as the tension on the thread became too little or the yarn was exhausted. Raising of the drop wire 112 caused roller 121 to engage the cam 120 thereby releasing latch 124 and allowing the handle 110 to be raised to stop position carrying with it arm 108 which moves the ratchet finger 106 forward about its pivot while it is in engagement with the teeth of rack 104, thereby swinging the package upwardly regardless of its diameter.

The winding mechanism may be restarted as soon as a new yarn has been joined to the end of the yarn on the package, and the starting is accomplished by restoring the parts to the position shown in Figure 28.

Means carried by the tender are provided for moving a fresh or reserve bobbin into winding off position, and these means cooperate with the bobbin support so that movement of the tender past the winding unit causes the bobbin holder to be shifted to its next position, and at the same time doffs the bobbin which has been exhausted.

As shown in Figures 2—A, 2—B, 3—A, 3—B and 7, an arm 200 is pivotally mounted on the tender about a horizontal axis parallel to the path of movement of the tender, and this arm 200 projects toward the bobbin support, being mounted on the pivot pin 201 which projects from the tender frame, and is thereby held against axial movement on that pin. The forward end of arm 200 is provided with a counterweight 202 while the other end nearest the bobbin support has secured to it a short rack section 203, which, in this instance, comprises a two-toothed rack. Upwardly extending from the longer end of the arm 200 is a rod 205 which, as will be later described more in detail, is lowered as the tender passes a unit which is still winding yarn from a bobbin to the package. An extension spring 206 is connected between rod 205, and an upright 207 of the tender frame and assists the counterweight 202 in swinging the arm 200 with its rack 203 into its normally raised position.

A mutilated sprocket 210 is mounted immediately below the base member 73 of the bobbin supply, and is rigidly connected with that base member. This sprocket is of preferably the same tooth form as the rack 203, and has three groups of two teeth each. Sprocket 210 is coaxial with the bobbin support shaft 74, its teeth lie directly in the normal path of movement of the rack 203 as it is moved relatively to the winding unit. This relative movement causes the teeth of the rack 203 to engage one of the pairs of the sprocket teeth to turn the bobbin support through one-third of a revolution, thereby effecting the movements of the three bobbin spindles as more fully

illustrated in Figures 21 and 27, and as the rack tooth 203 leaves sprocket 210 (dotted line positions of Figure 20) this one-third revolution of the bobbin supply has been completed, and a full bobbin has been moved from its reserve position to its running position, and the exhausted bobbin has been doffed from its pin and that pin has been restored to its normal parallel position.

As later pointed out more in detail, if the winding unit is still functioning as the tender passes, arm 200 and rack 203 are lowered so that the teeth of rack 203 do not engage the teeth of sprocket 210, and thereby the bobbin replenishing operation is omitted during that trip of the tender.

On the trailing side of the tender is provided a bobbin box into which the exhausted bobbins are doffed, and this bobbin box is preferably removable from the tender so as to facilitate clearing

20 the tender of used or exhausted bobbins. As embodied at the trailing side of the tender, articulately connected thereto so that it is drawn along by the tender, is provided a sheet metal box 220 which has an upper compartment 221 and lower compartment 222, the upper compartment preferably serving to receive a box of fresh bobbins, while the lower compartment preferably serves to receive the doff box for the exhausted bobbins. The lower compartment 222 is provided with an inner vertical wall 223 which extends upwardly for a considerable distance but leaves a sufficient space through which the bobbins may be projected as they are doffed from the bobbin supporting pin 79, and Figure 9 of the drawing 30 shows a bobbin as it is projected through that space and into the doff box.

The bobbin box may extend rearwardly of the tender for a considerable distance, the length depending upon the quantity of bobbins to be carried, and the leading edge of the bobbin box is connected to the trailing edge of the tender by means of the vertical hinge 224.

The lower wall 225 of the bobbin box is preferably sloping so that the doff box is inclined and the bobbins fall away from the rear of the box, while an upper wall 226 is likewise inclined and receives the box containing the fresh supply of bobbins.

Means are provided for facilitating the loading of bobbins onto the empty spindle of each bobbin supply and for this purpose there is provided a curved chute 230 extending in a generally upward direction, and conforming in general to the exterior shape of the supply mass used, and this chute is preferably so positioned that the new full bobbins are accurately guided along to the empty bobbin pin 79. Chute 230 is supported on an extended portion of pin 396 in the form of a bracket 55 60 231 at its upper end and is thereby made fast to and supported by the upper end of shaft 74, the upper end of the chute being open to receive a fresh fully wound bobbin as the operative drops it into the chute. The bobbin slides down the chute and is accurately located on the empty pin 79, that pin then being in the position corresponding to Figure 26.

Chute 230 is provided with a hinged portion 70 232, hinge 233 extending longitudinally of the chute, and hinge 233 is preferably a spring hinge so that the portion 232 is normally returned to a position in alignment with the remainder of the chute. The hinged portion 232 allows the fresh bobbin to move through the chute from the posi-

tion shown in Figure 26, as the bobbin supply is rotated by passage of the tender.

As the bobbin is dropped into the chute to replenish the bobbin supply, the operative keeps hold of the free end of the yarn and clips the yarn end in the slot 334 in the hook 335 which is also supported on the upper end of shaft 74, thereby holding the free end of the yarn ready for the assembling and knotting operations which are later to be performed.

Pneumatic means are provided for loosening the free end of the yarn from the package 45 being wound and for drawing from the package a predetermined length of this yarn. For this purpose there is provided a centrifugal blower 240 which is mounted on and carried by the tender and is driven at high speed from the motor 177 through pulley 241, belt 242, pulley 243 and shaft 244, the speed of the blower being sufficient to develop a rather high velocity of air. Supported on and above the tender is a sheet metal air conductor 250 which extends upwardly and toward the package 45 being wound, and this conductor comprises a pressure duct 251 and a suction duct 252, the pressure duct partially surrounding the suction duct throughout most of its length. The suction duct at its lower end 253 is connected to the intake of the centrifugal blower 240, while at its other end, the suction duct terminates in a relatively thin suction slot 254 which extends lengthwise of the package 45, and is preferably of a length substantially equal to or slightly longer than the package being wound. At its lower end, the air conductor 250 forms a chamber which includes the fan 240.

The suction duct 252 is composed of a sheet metal member rectangular in cross section which terminates in a circular portion 255, connected to a flexible hose 256 of relatively large diameter which forms the suction connection to the intake of the fan. Thus the fan 240 being driven continuously as the tender moves, a relatively strong blast of air issues from the forward end 258 of the air conductor which is directed against the surface of the package 45 and tends to loosen and dislodge the end of yarn sufficiently to free it almost immediately from the layers of yarn on the wound package, thereby allowing the loosened end to be picked up more readily and drawn into the suction duct 254 by the air being sucked therethrough.

Means are provided for periodically projecting the suction duct 252 toward the package being wound, 45, as the tender moves past the winding unit so as to enhance and render effective the suction operating through the slot or duct 254. The suction duct 252 is mounted on the tender by means of links 261, one link being pivoted on a pivot pin 262 carried on either side of the tender frame, the links having their upper ends pivotally mounted on a rod 263 supported by strap 264 attached to either side of the suction duct 252.

The forward end of the suction duct 252 is provided with a strap 266 extending upwardly therefrom and having a roller 267 freely rotatable at its upper end and adapted to ride on the upper surface of a cam plate 269 projecting upwardly from the air conductor 250, strap 266 extending through a suitable slot in the upper wall of the conductor 250. The shape of cam 269, and the action of the link 261 are such that the suction duct 254 moves toward the package in a generally forward and slightly downward direction.

Also connected to the shaft 263 is a link 270 75

having its forward end connected to the upper end of bell crank 271 which is mounted for rocking movement about a shaft 272 carried by the tender frame, and extending in a direction parallel to the direction of travel of the tender. Bell crank 271 is provided with a forwardly extending arm 273 to the forward end of which is attached the cam member 275. Cam member 275 engages with hub 296 at the adjacent end of starting lever 110 so as to depress arm 273 and the cam member 275 as the tender moves past a starting lever in knockoff position, thereby rocking the bell crank 271 to project the suction duct 252 until its slot 254 is closely adjacent the package 45.

At the forward end of the suction duct 252, and immediately below the slot 254 is mounted a roller 280 of moderate width freely rotatable in a bracket 281 which is pivotally mounted in the depending lugs 282 by means of shaft 284, the rear end 283 of the bracket 281 providing a stop to prevent excessive lowering of the roller 280. A friction pad 286 carried by plate 287 mounted on the under side of the suction duct 252 engages with the surface of the roller 280 restraining it against rotation when in the full line position of Figure 4.

Roller 280 moves forward with the suction duct 252 as the duct is projected towards the knocked-off package, and forms a reversing idler between the driving roll 32 and the partially wound package 45, which has been stopped and is in the dotted line position shown in Figure 4. As roller 280 moves in its dotted line position, 35 the package 45 is reversely rotated so that the yarn may be easily unwound beginning with its free end. As it is thus reversely rotated the free end necessarily passes close to the suction slot 254, and is sucked therein. This finding of the free end is facilitated and expedited by the blast of air issuing through the pressure nozzle 258 which prevents the adherence of the free end to the package as might otherwise occur. Inasmuch as roller 280 driving roll 32 and package 45 are all rotating while they are in contact, the axial movement of the roller 280 does not appreciably disturb the lay of the yarn on the surface of the package 45.

As the package 45 is thus reversely rotated, yarn is payed off from it into the suction duct 252, and the free end is carried into the flexible hose 256. Cam 275 is released from hub 296, in proper timed relation to insure that the free end of the yarn has been drawn into the flexible hose 256 but not into the fan 240, and as the suction continues the yarn is laid along the bottom wall of the suction duct 252 and across slots 290 and 291.

Suction duct 252 is fully restored to its original 60 position shown in full lines in Figure 4 by the positive action of cam 295 operating on the hub 296 projecting from the end of starting lever 110, and the suction duct 252 remains in this position until it approaches the next winding unit for the corresponding reversing and end finding operations.

The air blast issuing through the nozzle 258 and the suction through slot 254 also serve to keep the winding roll 32, package 45 and the adjacent parts free from excessive accumulation of lint. Most of this lint is sucked into the duct 252 and thence into the fan 240 where it is deposited in a dirt receptacle and is thereby removed from circulation. For this purpose the

fan is preferably a centrifugal fan of a type generally similar to that known as "Vortoclone."

In order to permit removal of the free length of yarn in the duct 252 from the duct, the lower trailing edge of duct 252 is preferably formed with a narrow slot 293 extending from the suction slot 254 past slots 290 and 291 so that a hook passing straight through either of the slots 290 or 291 may remove the yarn sideways through the duct.

Means are provided for engaging the yarn in the duct 252 and for removing it through the side slot 293. For this purpose each winding unit is provided with a hook 335 mounted on U-shaped arms 395 which in turn are supported on a rigid member 396 extending from the thread tensioning unit at the upper end of the shaft 74. Hook 335 is formed as an angled plate extending parallel to the direction of travel of the tender and having a lower slot 334 and an upper slot 399, these slots both being of considerable length, parallel to the direction of travel of the tender and opening rearwardly with respect to the direction of travel of the tender, being held, however, rigidly with respect to the winding unit so that the tender moves past them. The arms 395 hold the hook 335 in a fixed position so that the upwardly extending portion of hook 335 and the slot 399 may pass through slot 291 as the tender travels.

By this relative movement, the free end of the yarn overlying the slot 291 is threaded into the slot 399 and further movement of the tender causes the yarn to be pulled sidewise through the long side slot 293, the free end of the yarn being subjected to tension by the suction and velocity of the air in the hose 256. The free end of the yarn 300 is thus moved from its position as shown in Figure 5 to the position shown in Figure 5-A, closely positioning it with respect to the leading end of the replenishment bobbin, the end 301 of which had been previously inserted in slot 334 as the operative dropped the replenishment bobbin into the chute 230. Further movement of the tender of course causes the free end of the yarn 300 to be pulled from the hose 256 through the slot 293 so that the yarns 300 and 301 are assembled under light tension with their free ends on the side of hook 335 away from the package, and ready for the tying or knotting operation which might be performed manually, or with a manually actuated mechanical knotter, but is preferably carried out automatically.

A knotter 310 is carried by the tender and depends from its trailing side with its yarn receiving notches in a position to receive the yarns 300 and 301 on further movement of the tender, and other means are provided for actuating the knotter to cause the completion of the knotting operation by further relative movement with respect to the winding unit.

As illustratively shown, the knotter is of the conventional type manufactured and sold by Mill Devices Company and is adapted to tie a weaver's knot, this conventional type of knotter having been modified by the addition of suitable actuating members so that it may be mechanically actuated by the travel of the tender past the winding units.

Supporting means for the knotter are provided on the stationary housing duct 251 and attached to the suction duct 252 of the travelling tender is a channel shaped bracket 249. The stud 248 is rigidly fastened to a bracket 259, as is block 260 which supports the knotter arm 311 by a pivot 311A, the bracket 259 being an integral part of

the stationary housing blowing duct 251. When the suction duct 252 is extended one edge 249A of bracket 249 engages the supporting arm 311 of the knotter 310, causing the knotter 310 to swing downward into a position for engaging and tying together the free end from a supply bobbin with the free end from the package being wound.

As the tender in its regular travel around the winder passes a winding unit it advances the knotter 310 past each winding unit 30 and during the said advancement the knotter 310 performs its functions of uniting and trimming two strands of yarn.

Immediately after the knotter 310 has been lowered the advancing movement brings a dog 312 extending from the lower part of knotter 310 into engagement with the slot 337, said slot being formed between two trackway members 338 and 339 of the double slotted hook 335. The slot 337 holds the knotter 310 in controlled travelling position during the advancement of the knotter while performing the knotting operation.

Simultaneously with the extending of the suction duct 252 the knotter 310 is lowered so that the dog 312 can enter the slot 337 as the knotter 310 advances in its travel; also the nozzle end 254 of the suction duct 252 has been brought into close proximity to the peripheral surface of the wound package 45 of yarn and means, previously described, have caused the package to start to unwind. With the end of the strand on the package having been loosened, found and sucked and drawn away to a length extending beyond the transverse slots 290 and 291 in the suction duct a brake stops the unrolling of the package, the upper slot 399 and hook 335 draws the extended strand out of the suction duct 252 through the long narrow slot 293 and the suction duct 252 is then retracted up and back to its normal idle position, but the knotter has been retained in its lowered position by slot 337 and has also advanced to a position shown at Figure 32 ready to perform the actual knotting operation.

The actual knotting operation which is shown just to begin in Figure 32 and just finishing in Figure 33, in a very general manner is as follows: the throat in the knotter is divided into two different sets of notches by a tongue 313. The notch 314, above the tongue, receives the end 300 sucked from the unrolling package while the notch 315 below the tongue, receives the end 301 from the supply bobbin.

A revolvable trigger stud 316 suitably mounted in bearings in the knotter is held by a helical spring (not shown) under a torque strain in a clockwise rotation; fastened to the stud is an arc or quadrant gear 318 which, when brought into engagement with a short stationary rack 336 causes the quadrant gear 318 and stud 316 to turn in a counter clockwise rotation a sufficient amount to actuate the knotter in its knot tying operation. When the knotter has travelled the distance shown by the length of the rack 336 the quadrant gear 318 runs off the rack 336 and is released and the helical spring above-mentioned then rotates the stud in the opposite direction which frees the knotter of the tied strand. Immediately following the knotting operation, the knotter 310 will have advanced in its regular longitudinal travel with the tender, to the position shown in Figure 33, where the dog 312 is just about to be moved out of engagement with the slotted trackway 338 and 339 which will allow the knotter to be swung up and back to its normal idle position shown in Fig-

ure 34, by the pull exerted by the extension spring 319.

Due to the predetermined pitch diameter of the quadrant gear 318 and the position of the intermeshing stationary rack 336, the knotter is operated at a faster rate than the normal rate of speed of the travel of the tender, which in this embodiment is very desirable.

The complete knot tying operation is repeated at each winding unit where the suction duct is caused to function when a winding package has been stopped due to an end of a strand of yarn having passed off the drop wire detector and allowed said detector to move out of its yarn winding position.

After the trailing end of the yarn 206 has been joined to the leading end of the yarn 301, the winding of package 45 may be restarted, and in its further movement the tender causes starting arm 110 to be moved to restarting position and returned to running position. As embodied, cam 330 carried on a bracket arm 331 extending upwardly from the tender engages with roller 277 at the end of starting lever 110 and causes this lever to be forced downwardly through the position shown in Figure 28 and as the roller 277 rides off the lower end 332 of cam 330, lever 110 raises slightly to running position as shown in Figure 3-A. By this motion the package 45 has been lowered against driving roll 32, thread plate 103 has been lowered to thread the yarn into the guide 68 and winding has been resumed. By the same operation, and as more fully described in the patents referred to, the ratchet bar 104 has been positioned so as to provide for proper lifting of the package in the event of a yarn breakage or upon yarn exhaustion.

It is generally desirable that the yarn be wound under tension, and in accordance with the present embodiment of the invention, means are provided not only for tensioning the yarn as it is wound, but also for introducing the reunited strand of yarn into the tension mechanism and properly threading it so as to require no separate manual operation. As embodied, a pivoted finger 340 is mounted by its pivot 341 on a U-shaped bar 342 which extends rearwardly from the tension support bracket 343, the long end of the finger 340 being positioned over the bar 296. Bar 342 is spaced from bar 398 to provide a passageway 345 between them, and pivoted finger 340 extends in a slightly downward direction from its pivot 341 and is normally held by a light spring and gravity in its lowermost position, while its counterclockwise rotation is limited by stop pin 347. At its short end, nearest the package, finger 340 is provided with an arm extending substantially at right angles to the finger but in a slightly upward direction and this arm 348 serves to insure that the yarn 399 will be guided onto the finger 340 as winding is resumed.

The tension mechanism itself is of substantially conventional construction and comprises a base washer 349 having a central pin 350 over which is fitted the weight or tension cup washer 351 between which and the base washer the yarn passes.

After the knot 346 has been tied by the knotter 318, with the loose ends cut just beyond the knot, the yarn falls so as to overlie the inclined arm 348. As the winding is resumed, the oblique pull on the strand of yarn causes the yarn to move slowly to the left taking up the slack therein, and further winding pulls the yarn down on finger 340 into the slot 345 at the same time gradually swinging the

finger 340 in a clockwise direction until the yarn is carried between the tension washer guard 352 and the U-shaped rod 342, guard 352 also being carried by the bracket 343, and the arms of bar 342 having their upper faces substantially aligned with the space between base washer 349 and washer 351. A standard form of slub catcher 357 is also mounted on the bracket 343, its gap being aligned with the normal run of yarn.

Further pull on the yarn as the winding proceeds causes the yarn to be positioned between the base washer and top washer inasmuch as the axis of the bobbin is positioned slightly to the right of pin 350 when viewed from the position of Figure 6. Figure 6 shows an intermediate position of the yarn transfer after the knot has been tied and after the reunited strand is being positioned beneath the washer guard 352 to enter the tension mechanism. As soon as the yarn has run off the humped end 353 of finger 340, the finger 340 is free to return by a light spring and by gravity to the position shown in Figure 5, after which the winding proceeds until the yarn has been exhausted from the supply mass or until a break occurs in the yarn.

By reason of the slack existing in the yarn between the tying of the knot and the resumption of winding, and the delay between the resumption of winding and the transfer of the yarn beneath the washer guard 352 caused by the swinging of the finger 340, the knot 346 which has been tied in the yarn passes to the package without entering the tension and slubbing device, and there is no danger of the knot being snagged by the tension or the slub catcher.

Movement of the tender past the winding unit also serves to shift the yarn supply mechanism to bring a reserve yarn supply into feeding position through the operation of the two tooth rack 203 cooperating with the mutilated sprocket 210, as previously described. Means are provided, however, for causing such replenishment of the yarn supply only in case the particular winding unit is not winding thereby avoiding useless replenishment which would result in wastage of the yarn contained on partially exhausted bobbins from which additional yarn might otherwise be drawn.

Bobbin actuating rack 203 supported on the end of pivoted arm 200 is normally held by spring 206 in its raised position, as shown in Figure 3-A, and in the full line showing of Figure 19. In this position rack 203 engages with mutilated sprocket 210 in the manner shown in Figure 20, the full line showing of rack 203 corresponding to the initial engagement of the rack with the sprocket. The dotted line showing of rack 203 represents the end of its operation on sprocket 210, this rack having been moved through these positions by the travel of the rockable bell crank causing a one-third revolution of the sprocket and the yarn supply masses. During this one-third revolution, the exhausted bobbin in the position corresponding to Figure 22 was moved through the doffing positions and the empty bobbin pin was moved to the position of Figure 26 ready to receive a new yarn supply mass or bobbin. The previously replenished bobbin in the position of Figure 26 was moved to the active position of Figure 27 where it became exhausted and the exhausted bobbin in the position corresponding to Figure 27 was moved to exhausted position corresponding to Figure 22. In other words, each of the three bobbin pins was moved through one-third of a revolution in a clockwise

21

direction without disturbing the leading end of the yarn 301 which the operator had hooked into the slot 334.

In order to prevent this normal movement of the bobbin support in case yarn is still being wound from the bobbin in the active position, means are provided for lowering the rack supporting arm 200 to an idle or non-meshing position during the passage of the rack 203 past sprocket 210. As embodied, a rod 205 extends upwardly from the arm 200 and its upper bent end 208 lies in a plane at right angles to the rod 205 and is bent toward the direction of tender movement as well as toward the bobbins. Arm 110 is provided with a depending plate 111 so that with the arm 110 in running position, cam plate 111 engages bent end 208 to move rod 205 arm 200 and rack 203 from their full line positions to their dotted line positions as shown in Figures 18 and 19 thereby causing rack 203 to pass idly by mutilated sprocket 210 so that the bobbin shifting operation does not occur.

With arm 110 in knocked-off or raised position, as shown in dotted lines Figure 18 corresponding to a broken yarn or an exhausted supply, cam plate 111 does not engage with the bent end 208 so that the bobbin shifting operation and doffing of the exhausted bobbin does occur by the relative movement of the tender.

Figure 10 shows the preferred construction and shape of certain of the cams, and cam 275 and cam 295 are mounted on arm 273 pivotally carried by the shaft 272 on the tender. The upwardly inclined surface 275' of cam 275 engages with the hub 296 extending toward it from the end of arm 110 and as cam 275 is moved across hub 296, with hub 296 already in its extreme upper knocked-off position with the package also in knocked-off position, cam 275 is pushed downwardly projecting the suction nozzle toward the package.

Curved surface 275' merges into the flat 275'' to hold the suction nozzle close to the package for a short period of time sufficient to cause the end of the yarn on the surface of the package to be freed, sucked into the nozzle 254, and a sufficient length of free yarn paid off by the reverse rotation of the package 45 so that the free end of the yarn is drawn into the suction nozzle some distance past slot 291.

As hub 296 rides off the end of flat 275'', the upper face of hub 296 is engaged by the underface of the cam 295, also mounted on the arm 273 thereby positively rocking bell crank 271 in a counter-clockwise direction (Figure 4) to retract roller 280 and suction duct 252 thereby interrupting the reverse rotation of the package 45 and restoring the duct to its normal position where it remains until it reaches the next winding unit.

Figures 12 and 13 show the final stage of this retracting operation, and during this retracted operation hub 296 is supported against downward movement by means of roller 277 which rides on track 297 formed at the upper end of a bracket supported on the tender.

In the event that the package 45 is still winding as the tender approaches, in which case the starting arm 110 will be at its lower position (full line Figure 4), roller 277 first clears the lower surface of track 297. In the event that the yarn should break or become exhausted at this particular phase of the operation, track 297 would then hold the starting lever 110 in its lower po-

22

sition thereby preventing improper operation of the mechanism such as might otherwise occur.

Figures 14 and 15 show the initial engagement of inclined cam 330 with the starting lever roller 277, cam 330 being rigidly mounted on the tender and as the tender moves past starting arm 110, the starting lever is moved to its lowermost position (Figure 28) as the roller 277 rides off the bottom end 332 of the cam 330 (Figures 16 and 17).

In the foregoing description directed primarily to the construction of the present embodiment of the invention, the operation of certain of the parts of the mechanism have been described from beginning to end without reference in many cases to the timing of these operations with respect to the operation of other portions of the mechanism. Figure 35 of the drawings shows the time relation of the various operations with respect to a particular unit.

Point A may be assumed to represent a position of the tender with respect to a particular winding unit corresponding to the initial engagement of hub 296 with the curved portion 275' of cam 275. As the tender travels to the left the suction duct 252 is extended during the period of travel represented by the line B. The suction duct and idler roller 280 remain extended during the tender travel represented by the line C. During the travel represented by the line D, the suction duct and roller are being retracted, and during the initial portion of this travel as represented by the line F the yarn is engaged by hook 399 and is withdrawn from the suction duct through the side slot thereby assembling the yarn to be knotted.

The travel represented by the line G takes place and during that time the yarns 300, 301 are engaged by the knotter being clamped, trimmed and knotted. The line H represents the travel of the tender as the yarn supply means is rotated to shift the position of the bobbins and bring a reserve bobbin into running position.

The line I represents the doffing motion of the yarn supply holder (Figures 23-26). Coincidentally and as represented by the line J, the starting lever 110 is moved to restart the winding operation (Figures 14-16).

The line K represents the travel of the tender during the time the slack in the yarn is being taken up and the yarn is being threaded into the tension mechanism, while the line L represents the time during which the parts of the tender are idle with respect to the cooperating parts of the winding unit.

After this cycle of operations has been completed, the operations are repeated with respect to the next winding unit, and in many cases it will be found desirable that the operations should be initiated on one winding unit before the complete cycle of operation has been finished on the preceding winding unit, and in other cases, it will be found desirable that the complete cycle of operations on a winding unit be completed before the operations should be initiated on the next succeeding winding unit.

Of course it will be understood that the foregoing description with reference to the timing of the operations assumes that a package was not being wound at point A on the timing chart. In the event that winding was taking place at the time A, the starting arm 110 would be held in winding position by the stop motion latch during the tender travel represented by the line M thereby preventing reversing of the package 45, and shifting of the bobbin supply would be prevented

during the time represented by the line N by means of the action of cam plate 111 on the bent end 208 of rod 205.

The operation of the illustrated embodiment may be summarized as follows:

Assuming that the several winding units 30 are operating normally with motors 36 driving the roll shafts 33 and the cam shafts 55. The travelling tender 169 is moving around the group of winding units 30 by operation of its driving motor 177 which actuates the traction pulleys 164 engaging the rail 151 while the power is supplied to the motor and the tender is held in proper vertical position by means of the rollers 169 and the power rail 159. The fan 240 is at the same time driven continuously by the motor 177 to create suction in the duct 252 and pressure in the duct 250.

Most of the winding units, except a few in front of the tender, are still winding in the normal manner but certain of the winding units have stopped winding due to exhaustion of the yarn supply mass or breakage of the yarn, in which case those particular units will be at rest with the package 45 out of contact with the still rotating driving roll 32.

In each active winding unit 30, the package 45 being wound is resting on its driving roll 32 and is being rotated, while supported on the arm 46, to draw yarn from the yarn supply bobbin 71 through the tension and slubbing devices, as well as through the yarn guide 62 which is traversed back and forth across the package by means of the cylindrical cam 56 driven by shaft 55. In each winding unit, yarn detector 112 is held down by the yarn under normal winding tension, but in case the yarn breaks or becomes exhausted, detector 112 is raised to cause the package 45 to be raised from its driving roll 32 and at the same time starting lever 110 is raised to its upper or knocked-off position thereby stopping the winding on that particular winding unit.

In its circuit around the group of winding units, the tender moving at a substantially constant speed approaches a winding unit which is still winding in the normal manner, and passes by idly except that the upper bent end 208 of rod 205, engaging with the plate 111 depending from the end of the starting lever 110 swings the rack 203 out of its normal path so that it does not engage the teeth of sprocket 210 thereby preventing movement of the bobbin support.

As soon as the tender 160 approaches a winding unit 30 which has stopped for any reason, the relative movement of the tender and winding unit causes the actuation of the various parts through the coaction of the different cam mechanisms. The hub 296 at the end of the starting lever 110 engages with the inclined surface 275 of cam 275 thereby causing arm 273 to be depressed so as to project the suction nozzle 254 towards the stopped package.

Simultaneously, reversing roller 280 is positioned between the package 45 and its driving roll 32 so as to cause the package to be reversely rotated thereby permitting the loose end of yarn on the package to be drawn off by the suction and into the suction duct 252. The time of engagement of the roller 280 and the extension of the suction nozzle are such as to provide for drawing an approximately uniform length of yarn from the package into the suction duct, this length being sufficient to cause the yarn to overlie the slots 290 and 291.

During the period the suction nozzle is extend-

ed and the reversing roller is engaged with the package, air under pressure and at a considerable velocity is issuing from the forward end 258 of the air duct 250 and blows directly against the package thereby facilitating the freeing of the yarn end from the package so that the yarn end is almost immediately found by and sucked into the suction nozzle 254.

Prior to the retraction of the nozzle and roller from the package, yarn engaging hook 335 passed through slot 291 to remove the yarn end through the side slot 293, thereby assembling the end of the yarn extending from the package with the end of the yarn extending from the reserve bobbin, or other yarn supply, and which is held in the slot 334 of the same hook member.

After the yarn end has been drawn off for the required length and removed through the slot 293, the suction duct and roller are then retracted and positively restored to their original positions by engagement of the hub 296 with the under face of the inclined cam member 295, hub 296 being at that time supported by means of the roller 277 which rides across the upper face of the plate 297 carried by the tender.

After the yarn ends have been assembled and the suction duct 252 has been retracted, the ends of the two strands of yarn are tied together by the knotter 310 which has been swung down by means of the member 249 (Figure 31) and retained in its lowered position by means of the dog 312 becoming engaged in the trackway slot 337 and is actuated to tie the knot by means of the segmental gear 318 which is oscillated in correct timed relation by the rack 336, the knotter being moved by the tender while the rack is held stationary on the winding unit.

The action of the knotter is to tie and trim the ends of the two yarns together so that winding may be resumed, and the knotter is restored to its upper or idle position (Figure 34).

Simultaneously, the travel of the tender being to rotate the yarn supply mass holder to bring the reserve, or a new, bobbin into winding off position, as well as to begin the depression of the starting lever 110, by which the package 45 is again lowered into contact with the driving roll 32 so that winding may be resumed. As the tender moves, the rack 203 is carried along with it and the cycle of operations illustrated in Figures 21 to 27 is carried out whereby the three bobbins are each rotated one third of a revolution to bring each into its next position. Thereby, the reserve bobbin is moved to active position, the active bobbin is moved to inspection position, and the empty pin is moved to loading position where it may be again loaded by the operative who drops a new, full bobbin on the pin and at the same time inserts the free end of the yarn in the hook 334, the exhausted bobbin being doffed as it moves from inspection position.

The depression of the starting lever to resume winding is effected by the cams shown in Figures 14 to 17. As the cam 330 is moved by the travel of the tender, it engages with the roller 277 to depress the lever 110 by which the package 45 is again lowered into contact with the driving roll 32 to resume winding, at the same time resetting the yarn detector and knock-off mechanism.

The resumption of winding causes the yarn to be pulled free from the knotter and over the finger 340 which is thereby swung to insert the yarn into proper position in the tension and slubbing mechanism with the knot beyond the slubbing device.

Thereafter, the tender continues movement to the next winding unit, and the operations previously described are repeated on that unit if the unit has been stopped by exhaustion or breakage of the yarn, but in case the unit is winding the tender unit passes idly by the winding unit.

When the packages have been built to the proper size, the operative individually removes them as they become full, thereby preventing overwinding of the packages. Also as the operative follows the tender, she may replenish the empty bobbin supporting pins, or remove the partially exhausted bobbins and replace them on the empty bobbin pins, as well as remove the doffed bobbins from the bobbin box which trails the tender and is moved along with it.

The invention in its broader aspects is not limited to the specific mechanisms shown and described but departures may be made therefrom within the scope of the accompanying claims without departing from the principles of the invention and without sacrificing its chief advantages.

What we claim is:

1. In a multi-unit winding machine, the combination of means for supporting and rotating a yarn package, a movable support for a plurality of supply bobbins from which yarn is wound on the package, means for doffing an empty bobbin from the support, a yarn detector normally held in one position by yarn extending from a bobbin to the package and periodically operating means controlled by the detector for rotating the support after the yarn has been exhausted from a bobbin.

2. In a multi-unit winding machine, the combination of means for supporting and rotating a yarn package, a rotary support for a plurality of supply bobbins from which yarn is wound on the package, periodically operating means for rotating the support, means for doffing an empty bobbin from the support and means controlled by a yarn from a bobbin to the package for preventing operation of the support rotating means until the yarn has been exhausted.

3. In a multi-unit winding machine, the combination of means for supporting and rotating a yarn package, a rotary support for a plurality of supply bobbins from which yarn is wound on the package, periodically operating means for rotating the support, means for doffing an empty bobbin from the support, a yarn detector normally held in winding position by yarn extending from a bobbin to the package and means controlled by the detector for preventing operation of the support rotating means until the yarn has been exhausted.

4. In a multi-unit winding machine, the combination of means for supporting and rotating a yarn package, a travelling tender movable past the package, and an idler roller carried by the tender and movable into contact with the package, a suction duct to suck a yarn end from the package and rotating means including a roller contacting with the package to reverse rotation of the package.

5. In a multi-unit winding machine, the combination of means for supporting and rotating a yarn package, a travelling tender movable past the package, an idler roller carried by the tender and movable into contact with the package and its rotating means to reverse rotation of the package, and means for timing the contact of the roller with the package and rotating means

to control the length of yarn to be drawn from the package.

6. In a multi-unit winding machine, the combination of means for supporting and rotating a yarn package, a tender movable relatively past the package, a wide air nozzle carried by the tender and movable toward and from the package being wound to suck a yarn end from the package, and an idler roller carried by the tender adjacent the nozzle and movable into contact with the package and its rotating means to reverse rotation of the package.

7. In a multi-unit winding machine, the combination of means for supporting and rotating a yarn package, a travelling tender movable past the package, an idler roller carried by the tender and movable into contact with the package and its rotating means to reverse rotation of the package, and means to control the length of yarn to be drawn from the package.

8. In a multi-unit winding machine, the combination of means for supporting and rotating a yarn package, a tender movable relatively past the packages, a wide air nozzle carried by the tender and movable toward and from the package being wound to suck a yarn end from the package, an idler roller carried by the tender adjacent the nozzle and movable into contact with the package and its rotating means to reverse rotation of the package, and means to control the length of yarn drawn from the package.

9. In a multi-unit winding machine, the combination of means for supporting a package core on which yarn is to be wound, a driving roll on which the package rests for rotating the package, a divided air nozzle and means for blowing and sucking air through the different parts of the nozzle to free a yarn end from the package and suck the yarn end into the nozzle.

10. In a multi-unit winding machine, the combination of means for supporting a package core, a surface driving roll for rotating the package, a travelling member moving past the package, an idler roller carried by the travelling member to be interposed between the driving roll and package for reversely rotating the package and means for finding and drawing from the package a loose yarn end.

11. In a multi-unit winding machine, the combination of a support for a surface driven package, a driving roll, a travelling member moving past the package, an idler roller carried by the travelling member and movable into contact with the package and roll for reversely rotating the package, means for finding and drawing from the package a loose yarn end, and means for moving the idler roller into package reversing position when the package is not driven by the roll.

12. In a multi-unit winding machine the combination of a surface driven winder to wind yarn from a yarn supply having a driving roll and a package movable relatively into and out of driving relation thereto, a yarn detector to stop the winder on absence of the yarn at the detector, and a reversing idler roller operating periodically and moving into contact with the package and driving roll to reverse rotation of the package when yarn is absent at the detector, means for assembling the end of a reserve yarn supply with the end of the yarn wound on the package, means for moving the assembling means past the unit, means carried with the assembling

means past the winding unit for resetting the detector and restarting the winding.

13. In a multi-unit winding machine, having means for supporting and rotating a package core, a movable support for simultaneously supporting a plurality of yarn supply masses and their holders, one of said yarn supply masses supplying yarn to the package while another serves as a reserve package, a yarn detector between the supply mass and package, means for moving the reserve package into supply position after the detector has indicated absence of yarn and means for removing the holder of the first supply from its support as the yarn supply mass is moved.

14. In a multi-unit winding machine, having means for supporting and rotating a package core, a movable support for simultaneously supporting a plurality of yarn supply masses and their holders, one of said yarn supply masses supplying yarn to the package while another serves as a reserve package, a yarn detector between the supply mass and package, means for moving the reserve package into supply position after the first supply has been exhausted, means for removing the holder of the first supply from its support as the yarn supply mass is moved, and means for assembling a yarn end from the package and from the reserve package.

15. In a multi-unit winding machine having means for supporting and rotating a package core, means for supporting a plurality of yarn supply masses from one of which yarn is drawn by the package and another yarn supply mass constituting a reserve yarn supply, a traveller periodically moving past the package and supporting means and means carried by the traveller for moving the reserve yarn supply mass into supply position when the yarn is exhausted from another supply mass.

16. In a multi-unit winding machine having means for supporting and rotating a package core, means for supporting a plurality of yarn supply masses from one of which yarn is drawn by the package and another yarn supply mass constituting a reserve yarn supply, a yarn detector responsive to the absence of yarn between the supply and package, a traveller periodically moving past the package and supporting means and means carried by the traveller and controlled by the yarn detector for moving the reserve yarn supply mass into supply position when the yarn is exhausted from another supply mass.

17. In a multi-unit winding machine having means for supporting and rotating a package core, a movable support for simultaneously supporting a plurality of yarn supply masses from one of which yarn is drawn by the package and another yarn supply mass constituting a reserve yarn supply, a yarn detector rendered operative by absence of yarn between the supply and package and

periodically operating means controlled by the detector for moving the reserve yarn supply mass into supply position.

18. In a multi-unit winding machine, the combination of means for supporting and rotating a yarn package, a rotary support for a plurality of yarn supply packages from which yarn is wound on the rotating package, a tender movable relatively past the packages, a nozzle carried by the tender extendable toward and retractable from the package being wound to suck a yarn end from the package, a roller carried by the nozzle and movable into contact with the package to reverse its rotation, means for timing the period of extension of the nozzle to control the time of contact of the roller and package whereby the end of yarn drawn from the package will be of predetermined length.

19. In a multi-unit winding machine, the combination of a travelling tender, a blower, and an air duct telescopically connected therewith, said blower and duct being carried by the tender, and means for intermittently extending the air duct to be closely adjacent a winding package when in its fully extended position, said air duct terminating in a thin nozzle substantially as wide as the package.

20. In a multi-unit winding machine, the combination of means for supporting and rotating a package core on which yarn is to be wound, an air nozzle mounted to move past the package and in close proximity to the periphery thereof and means for directing air through the nozzle over the length of the package to free a yarn end thereon.

21. In a multi-unit winding machine, the combination of means for supporting a package core on which yarn is to be wound, a driving roll on which the package rests for rotating the package, an air nozzle mounted to move past the package, means to direct the nozzle into close proximity to the periphery of the package and means for blowing air through the nozzle and directing a current of air over the length of the package, to free a yarn end thereby.

22. In a multi-unit winding machine, the combination of means for supporting and rotating a package core on which yarn is to be wound, a thin wide air nozzle mounted for movement past the package surface substantially as wide as the length of the package, means for moving the nozzle radially toward and away from the package, means for sucking air through the nozzle to draw a free end of yarn into the nozzle in extended position and means for removing the yarn end from the nozzle while still extended to assemble the yarn end with a reserve yarn end.
